DESIGN FOR A CHILD'S TOILET CHAIR

Walter Jones, Edwardsville, Ill., assignor to Illinois Lumber Company, Incorporated, Edwardsville, Ill., a corporation of Illinois

Application April 3, 1944, Serial No. 113,122

Term of patent 3½ years

(Cl. D15—1)

To all whom it may concern:

Be it known that I, Walter Jones, a citizen of the United States of America, residing at the city of Edwardsville, county of Madison, State of Illinois, have invented a new, original, and ornamental Design for a Child's Toilet Chair, of which the following is a specification, reference being had to the accompanying drawing, forming a part thereof,

In the drawing: Figure 1 is a side elevational view of a child's toilet chair, showing my design; Figure 2 is a front elevational view; Figure 3 is a rear elevational view; and Figure 4 is a top plan view thereof.

I claim:

The ornamental design for a child's toilet chair, substantially as shown.

WALTER JONES.
